UNITED STATES PATENT OFFICE.

THEODORE W. KLOMAN, OF PARK RIDGE, NEW JERSEY.

INTERNAL-COMBUSTION ENGINE.

1,399,262.

Specification of Letters Patent.

Patented Dec. 6, 1921.

Application filed November 6, 1920. Serial No. 422,170.

To all whom it may concern:

Be it known that I, THEODORE W. KLOMAN, a citizen of the United States, residing at Park Ridge, in the county of Bergen 5 and State of New Jersey, have invented a certain new and useful Improvement in Internal-Combustion Engines, of which the following is a specification.

The invention relates to motors having 10 two or more cylinders arranged side by side, and more particularly to the valve for controlling the admission of fuel gas to such cylinders and the escape of exhaust therefrom.

15 The object of the invention is to provide a positively operated hollow rotary cylindrical valve having ports and pockets therein coöperating with the cylinder ports and inlet and exhaust passages of the valve casing, whereby the fuel gas is distributed uniformly 20 to all the cylinders and its travel from inlet to exhaust is exactly the same for all such cylinders.

Another important object is to utilize 25 fully the cooling effect of the incoming fuel gas by leading it into direct contact with the warmest interior portions of the valve in its traverse through the latter to the cylinder ports, and to bathe the exterior of 30 the valve in such incoming gas.

The invention consists in certain novel features and details of construction and arrangement of ports and passages by which the above objects are attained, to be hereinafter described and claimed.

The accompanying drawings form a part of this specification and show the invention as it has been carried out in practice in a four cylinder engine.

40 Figure 1 is a plan view of the engine with the bonnets of the valve casing removed.

Fig. 2 is a vertical longitudinal section taken through the axial lines of the cylinders, and showing the valve in side view.

45 Figs. 3, 4, 5 and 6 are vertical transverse sections taken axially of the cylinders on the lines 3-3, 4-4, 5-5 and 6-6 respectively in Fig. 2, showing the valve ports and passages in corresponding positions, and 50 with the bonnets omitted.

Fig. 7 is a cross-section through the valve, taken on a line between adjacent inlet ports.

Fig. 8 is a vertical longitudinal section through adjacent end portions of one of 55 the bonnets, valve casing and valve, cor-

responding to a portion of Fig. 2 and on a larger scale.

Similar letters of reference indicate the same parts in all the figures.

A¹, A², A³ and A⁴ are the cylinders arranged side by side in alinement, shown as in two pairs, each pair having a hollow cylindrical valve portion, marked B¹ B² respectively and the two portions joined end to end to revolve as one. The valve 60 extends across the top of the cylinders and is inclosed in a chambered valve casing A serving also as the heads for the cylinders.

The valve portions B¹ B² are each closed at the ends and at the outer end of B¹ is an 65 axial stud B³ by which the valve is rotated through the medium of a pinion B or other means from the main shaft, not shown, or other continuously moving part.

Over each valve portion is a bonnet C 70 serving as a manifold for fuel gas received from a carburetor, not shown, through a pipe and branches indicated in dotted lines in Fig. 2, leading to the bonnets of the pairs of cylinders.

The casing A is cored to provide a water-jacket and has exhaust passages d¹, d², d³ and d⁴ formed therein extending laterally and connecting with an exhaust manifold D.

Fuel gas is delivered to each pair of cylinders through long open ports C¹ C² beneath the bonnets, each extending longitudinally of the casing nearly the entire length of each valve portion and of considerable width so that a large portion of the exterior 80 surface of the valve is exposed to and bathed in the cool gas at all times, new surfaces being successively presented as the valve revolves. The ports C¹ C² contain

each a shell or lining C³ in the form of a 85 grate having bridges C⁴ extending diagonally across the port and is arranged to take the upward thrust of the valve as will be described.

In the lower face of the casing A, below 100 the valve, are cylinder ports a¹, a², a³ and a⁴ each communicating with its cylinder and in line with the inlet ports of the valve. The inlet ports for the cylinder A¹ are located oppositely to each other in the valve 105 portion B¹ and are marked F¹ F², and the ports for the cylinder A² are similarly located but advanced circumferentially and marked F³ F⁴. The inlet ports in the valve portion B² for the cylinders A³ A⁴ are simi- 110

larly arranged and advanced and are marked $F^5 F^6$ for the cylinder A^3 , and $F^7 F^8$ for the cylinder A^4 . These inlet ports register with the corresponding cylinder ports as they are presented to the latter by the rotation of the valve, and permit fuel gas to flow from the bonnets C across and through the valve to the cylinder ports.

The spent gases from the cylinders escape through the same cylinder ports to channels or pockets formed in the valve and open on the exterior thereof. At one end the exhaust pockets register with the ports and at the other with the exhaust ports or passages in the valve casing and extend partially around the valve to thus register. They are arranged oppositely for each cylinder and are advanced circumferentially in the same manner as the inlet ports. The pockets form swells of approximately semi-circular section on the interior of the valve, as shown in Fig. 7.

The exhaust pockets for the cylinder A^1 are marked $G^1 G^2$ and those for the cylinder A^2 are marked $G^3 G^4$. The pockets $G^5 G^6$ for the cylinder A^3 , and $G^7 G^8$ for the cylinder A^4 are similarly arranged but extend oppositely so that the exhaust passages $d^1 d^2$, d^3 and d^4 may lie close together, at the center of the casing A .

Figs. 3, 4, 5 and 6 show the positions of the inlet ports of the valve relatively to the cylinder ports and pistons in the cylinders A^1 , A^2 , A^3 and A^4 in Fig. 2; in cylinder A^1 the charge of gas has been taken in through the inlet ports $F^1 F^2$ and the piston has commenced its upward compression stroke; cylinder A^2 shows the condition immediately following explosion, the cylinder port a^2 is sealed and the piston has commenced its downward effective stroke; in cylinder A^3 the piston has commenced its downward suction stroke and gas is entering through the inlet ports $F^5 F^6$ and cylinder port a^3 , and in cylinder A^4 the piston is beginning its upward exhaust stroke and the spent gases are being forced out through the cylinder port a^4 and exhaust pocket G^7 .

The pressures on the valve due to explosion and compression are upward, tending to lift the valve and thus cause excessive wear in the upper portion of the bore in which the valve is mounted. To take this strain and avoid distortion of such bore and the consequent friction and leakage, the lining C is introduced having its under surface and bridges shaped to match the curvature of the valve and lie upon the latter, and is held down to resist the lift of the valve by adjusting screws H extending loosely through the margins of the bonnets C and engaged with the ends of the lining as in Fig. 8. The screw is held in engagement with the bonnet by a lateral screw H' extending through the latter into a circum-

ferential groove h in the adjusting screw H . By turning the screws H the lining is forced downwardly into the desired contact with the valve.

It will be noted that the interior of the valve is filled with cool gas entering through the inlet ports, and that the exterior is bathed in the cool gas contained in the bonnets and long ports $C^1 C^2$ so that the temperature of the valve is kept as low as practicable and as nearly uniform as possible. It will also be noted that the fuel gas flows directly and diametrically through the valve from the bonnet to the cylinder port of each cylinder and strikes upon the exhaust pocket through which the hot spent gases have just passed, as in Fig. 5, thus bathing the hottest portion of the valve in cool gas without retarding the flow to the cylinder.

The distance traveled by the incoming gas in passing from the ports $C^1 C^2$ through the valve to the cylinder ports is the same for each cylinder, and as the exhaust pockets are all of the same length and lead to correspondingly located exhaust passages the travel of the hot spent gases from the cylinder ports to the exhaust passages is the same for all the cylinders.

These features of uniformity of gas-travel insure uniformity of action in the several cylinders and in the power developed beside maintaining the valve at a uniform temperature throughout which avoids unequal expansion and insures smooth frictionless valve action and correspondingly long service.

The valve is lubricated by supplying lubricating oil to the fuel gas which is thus distributed over the exposed surfaces of the valve in the long ports $C^1 C^2$.

I claim:

1. In an internal combustion engine, a plurality of cylinders set side by side each having a cylinder port, a rotatable hollow cylindrical valve having oppositely located inlet ports leading from the exterior to and communicating with the interior thereof in order to bathe such interior with intake gases and matching to said cylinder ports, arranged to receive fuel gas through one of said inlet ports and cause such gas to flow diametrically and directly across the interior of said valve and through the other of said inlet ports to one of said cylinder ports.

2. In an internal combustion engine, a plurality of cylinders set side by side each having a cylinder port, a rotatable hollow cylindrical valve having oppositely located inlet ports leading from the exterior to and communicating with the interior thereof and matching to said cylinder ports, exhaust pockets between said inlet ports circumferentially of said valve, said inlet ports arranged to receive fuel gas through one of said inlet ports and cause such gas to flow diametrically and

directly across the interior of said valve and through the other of said inlet ports to one of said cylinder ports and to bathe said pockets in such traverse.

5 3. In an internal combustion engine, a plurality of cylinders set side by side each having a cylinder port, a rotatable hollow cylindrical valve having oppositely located radial inlet ports leading from the exterior to and communicating with the interior thereof, and oppositely located exhaust pockets in pairs between said inlet ports circumferentially of said valve, said inlet ports arranged to receive fuel gas to one of said inlet ports and cause such gas to flow diametrically and directly across the interior of said valve and through the other of said inlet ports to one of said cylinder ports, and to bathe a pair of said exhaust pockets in such

20 traverse.

4. In an internal combustion engine, a plurality of cylinders set side by side each having a cylinder port, a valve casing, a hollow cylindrical valve closed at the ends and rotatably mounted in said casing and having pairs of oppositely located inlet ports in circumferential alinement, a fuel gas chamber in said casing extending longitudinally of said valve and partially inclosing it, said inlet ports arranged to register with said chamber and with said cylinder ports and adapted to receive such gas from said chamber through one of said inlet ports and deliver it directly and diametrically across the in-

terior of said valve through the other of said inlet ports to said cylinder port, such gas in such traverse entering and serving to cool the interior of said valve, and the gas in said chamber serving to cool the exterior of said valve.

5. In an internal combustion engine, a plurality of cylinders set side by side each having a cylinder port, a valve casing, a hollow cylindrical valve closed at the ends and rotatably mounted in said casing and having pairs of oppositely located inlet ports in circumferential alinement, and pairs of exhaust pockets open on the exterior of said valve and located between said inlet ports circumferentially of said valve, a fuel gas chamber in said casing extending longitudinally of said valve and partially inclosing it, said inlet ports arranged to register with said chamber and with said cylinder ports and adapted to receive such gas from said chamber through one of said inlet ports and deliver it directly and diametrically across the interior of said valve through the other of said inlet ports to said cylinder port, such gas in such traverse entering and serving to cool the surfaces of said pockets and adjacent interior surfaces of said valve, and the gas in said chamber serving to cool the exterior of said valve.

In testimony that I claim the invention above set forth I affix my signature.

THEODORE W. KLOMAN.
